UNITED STATES PATENT OFFICE

2,435,271

ENVELOPE OPENER

Henry L. Dowell, Athens, Tex., assignor of one-half to Leon Barron, Athens, Tex.

Application April 24, 1946, Serial No. 664,530

2 Claims. (Cl. 164—41)

1

This invention relates to envelope openers, and particularly to an envelope opener wherein one end of an envelope to be opened is positioned in a slot formed in the upper surface of the body of the opener, to be cut by a pivoted blade mounted for movement directly under the slot, the end of the envelope extended through the slot and lying within the path of travel of the blade, to be cut away by the blade, to permit the ready removal of the contents of the envelope.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a perspective view of an envelope opener constructed in accordance with the invention.

Figure 2 is a bottom view of the upper section of the body.

Figure 3 is a sectional view taken on line 3—3 of Figure 2.

Referring to the drawings in detail, the body of the envelope opener is indicated by the reference character 5 and is preferably box like in formation, the body comprising an upper section 6 and a lower section 7, securely connected by means of screws 1', so that the body portion may be conveniently opened should it be desired to repair or adjust the mechanism of the opener.

The upper section 6 is formed with a slot 8 through which the ends of envelopes are extended, when it is desired to cut away a portion of the envelope to gain access to the interior thereof.

Rising from the body, and being disposed at opposite sides of the slot 8, are transparent members 9 which are arranged in spaced relation with respect to each other, the transparent members 9 having their ends disposed within grooves formed in the inner surfaces of the brackets 10 that are secured to the upper surface of the upper section 6.

The upper recess 6 is formed with a recess extending inwardly from the inner surface thereof, the recess providing a compartment in which the plate 11 is securely held, the plate being provided with a slot 12 that registers with the slot 8 of the upper section. Directly under the slot 12 is a plate 13 that extends transversely of the body

2

throughout the length of the slot, the ends of the plate 13 being secured to the brackets 14 secured within the slot, so that the plate 13 is supported in spaced relation with the plate 11.

5 This plate provides a support for the envelope and prevents the envelope which is inserted in the slot from passing too far into the body of the envelope opener. The distance between the plate 13 and plate 11 is such that only a small portion 10 of the end of the envelope will be cut away, thereby insuring against cutting the contents of the letter during the cutting operation to open the envelope.

Secured to the plate 11 and extending along 15 one edge of the slot 12, is a stationary blade 15 which cooperates with the pivoted blade 16 that is pivotally connected to the plate 11, by means of the screw 17. The operating lever is indicated by the reference character 18 and has its inner end 20 pivotally connected within the cut-out portion of the upper section, as clearly shown by Figure 2 of the drawings, the free end or handle 19 of the operating lever being extended through a slot formed in one end of the upper section 6, where 25 it may be easily operated by the person using the device. A guide plate indicated at 20 is secured adjacent to the slot through which the lever 18 extends to support the lever as it is being moved 30 to operate the movable blade. A link indicated by the reference character 21 connects the pivoted blade 16 with the lever 18, so that as the lever 18 is moved forwardly the pivoted blade 16 is moved into cooperative relation with the blade 15, cutting away a portion of the envelope positioned in the slot.

A coiled spring indicated by the reference character 22 is mounted within the body and has one of its ends anchored at 23, while the 40 opposite end thereof is secured within the openings 24 formed in the lever 18.

Positioned directly under the slots of the body through which the envelope is extended, is a 45 sliding drawer 25 into which the clippings from the envelope fall so that they may be readily removed when the drawer is withdrawn.

In order to facilitate the operation of the lever 18, a finger piece 26 is provided on the upper surface of the upper section 6, to accommodate the thumbs of the operator while the second finger is used in operating the lever.

Due to the foregoing, it is believed that the construction and operation of the device will be 55 clearly understood, and that further detailed description of the device is unnecessary.

What is claimed is:

1. An envelope opener comprising a body having a slot formed in the upper surface thereof, spaced transparent guide members positioned on opposite sides of the slot and adapted to guide an envelope to the slot, a supporting plate secured within the body portion directly under the slot and in spaced relation with the slot, said supporting plate providing a support for an envelope held within the slot, a stationary blade secured adjacent to one edge of the slot, a pivoted blade mounted within the body and adapted to move under the slot in cutting relation with the stationary blade, whereby an envelope resting on the plate is cut.

2. An envelope opener comprising connected upper and lower sections, said sections being hollowed out and providing a hollow body, the upper section having a transversely disposed slot formed in the upper surface thereof, transparent guide members arranged on opposite sides of the slot

5
10

and adapted to direct an envelope to the slot, a stationary blade secured within the body portion adjacent to the slot, a pivoted blade cooperating with the stationary blade and cutting an envelope held within the slot, and means within the body portion providing a stop for the envelope positioned within the slot, whereby the envelope is held in cutting relation with respect to the blades.
